DOOR OPERATING MECHANISM

Harry G. Ainsworth, Aurora, Ill.

Application December 30, 1929
Serial No. 417,381

23 Claims. (Cl. 268—65)

The present invention relates to door-operating mechanism of the type commonly employed for operating garage doors and other like closures. In the preferred embodiment herein shown, the invention is concerned primarily with that type of door-operating mechanism wherein the electric motor and the principal door-operating parts driven thereby are mounted directly on the door to move therewith, but included within the invention are certain elements and combinations of parts which may be advantageously embodied in other types of door-operating mechanisms.

One of the important objects of the invention is to provide improved overload relief means for the purpose of preventing injury to the door, its operating mechanism, or the electric motor, in the event that the normal operation of the door should be interfered with or obstructed, or if some other abnormal condition should arise. For example, in the case of a garage door, the present overload relief means will prevent the possibility of injury if the operating mechanism should be inadvertently energized with an automobile blocking either movement of the door, or if because of any other condition the door should be incapable of normal movement with the electric motor energized. The present overload relief mechanism is entirely automatic in its operation, it can be adjusted for different operating conditions, and does not need to be reset after performing its relief function.

Another important object of the invention is to provide manually operated release means designed for the purpose of quickly and easily permitting manual operation of the door independently of the operation of the electric motor. For example, in the event of failure of the current supply, possibly in the case of a fire, this manually operated release means permits the door instantly to be disconnected from the electric motor so that the door can be moved immediately.

The automatic switch apparatus controlling the circuit of the electric motor is preferably governed by cam means, and another object of the invention is to provide a construction of door-operating mechanism in which the automatic actuation of the above mentioned overload relief means will not disturb the proper timed relation of the cam means with respect to the position of the door. In this regard, it is another object of the invention to provide a construction wherein after actuating the manually operating releasing means the re-establishment of the operating relation between the electric motor and

the door can only be effected with the door in properly timed relation to said cam means.

Another object is to provide an improved motion transmitting relation between the aforesaid cam means and the automatic switch means which governs the stopping and reversing of the electric motor.

A further object is to provide an improved mounting and adjustable relation of the two cams constituting this switch actuating cam means.

A further object is to provide improved means for preventing the accidental condition arising of the motor continuing to operate in the same direction after the door has reached the predetermined limit of its movement and after the automatic reversing switch has been thrown.

Such continued running of the motor in the same direction is a possible condition arising in alternating current installations, brought about by reversed actuation of the manual starting switch before the door has completed one cycle of movement, and in the absence of means for preventing such condition it may cause injury to the door-operating mechanism or movement thereof to an abnormal position.

A further object is to provide an improved combination and arrangement of speed reduction mechanism between the electric motor and the crank arm which swings the door. Preferably this mechanism includes a belt drive which serves as an additional overload relief means, and the arrangement is such that the weight of the electric motor is utilized in constantly maintaining this belt at the proper driving tension.

Other objects and advantages of the invention will be apparent from the following description of one preferred embodiment thereof. In the accompanying drawings, illustrating such embodiment:

Figure 1 is an elevational view showing the mounting of the door-operating mechanism on a single panel swinging door;

Figure 2 is a plan view thereof, illustrating the door in its open position in dotted lines;

Figure 3 is a side view of the door-operating mechanism on a larger scale;

Figure 4 is a front elevational view of the same, a portion of the housing being broken away to illustrate the worm drive;

Figure 5 is a transverse sectional view through one of the feet of the motor, taken approximately on the plane of the line 5—5 of Figure 4, and illustrating the sliding support of the motor on the base plate;

Figure 6 is a vertical axial sectional view

through the main-operating parts of the mechanism;

Figure 7 is a transverse sectional view taken approximately on the plane of the line 7-7 of Figure 6 and looking downward;

Figure 8 is a similar sectional view taken approximately on the plane of the line 8-8 of Figure 6 for illustrating the cams and the movement of the switch actuating yoke which is 10 oscillated by the cams;

Figure 9 is a vertical sectional view through the cams and yoke taken approximately on the plane of the line 9-9 of Figure 8;

Figure 10 is a sectional view taken approximately on the plane of the line 10-10 of Figure 8, illustrating the operative connection between said yoke and the switch arm; and

Figure 11 is a detail view showing the adjustment afforded between the swinging end of the 20 crank arm and the link connected to the door frame.

Referring first to Figures 1 and 2, I have illustrated the present mechanism arranged for operating a door 14 which is suitably hinged at 15 to the side jamb 16 of a door-way 17. All of the main operating parts, including the electric 25 motor, the reduction gearing, overload slippage clutch, and manual releasing means are embodied in an operator unit, designated 18 in its 30 entirety. Such operator unit serves to swing a crank arm 19 which is pivotally connected at its outer end with a link 21. It is the relative angular movement between this crank arm and link which serves to swing the door between its open 35 and closed positions. In most installations, such as for operating a garage door and the like, the preferred practice is to mount the operator unit 18 directly on the swinging door and to connect the link 21 to the top frame of the doorway, as 40 by a pivot bracket 22 stationarily secured to said frame member, as illustrated in Figure 2.

However, the present mechanism has a wide 45 variety of other uses, such as for operating gates, wall panels, concealed closures, etc., and in some 50 of these installations it may be desirable to reverse the above relation by mounting the operator unit 18 on the frame of the closure opening or on some other stationary part, and by connecting the link 21 with the closure or like moving element. 55 Moreover, in Figures 1 and 2 the mechanism is shown as operating a single door panel, but in many installations the device will operate folding doors comprising two or more panels hinged together with the folding panels running on 60 trolley tracks. I have only shown the door at one side of the doorway but in most installations a companion door will swing from the other side of the doorway, having its own operator 18 mounted thereon and with the two electric 65 motors connected for simultaneous operation.

Such arrangement has not been illustrated because it is well known to those skilled in the art.

Referring now to the construction of the operator unit 18, and with reference to Figures 3 and 4, it will be seen that the different parts of this unit are assembled upon a base plate 25 which is rigidly secured to the inner side of the door 14 adjacent to the upper edge thereof. Mounted on the lower portion of this base plate is the electric motor 26. Mounted on the upper portion of said base plate is the housing 27 which incloses the reduction gearing and supports the rotating elements of the operator unit. The armature 70 shaft of the motor carries a pulley 28 which

transmits a drive through a belt 29 to a relatively large pulley wheel 31 mounted on a horizontal shaft 32 extending into the housing 27. The drive through this belt 29 constitutes one speed reduction, and also affords an overload slippage 80 connection for preventing stalling of the motor or injury thereto for taking care of an abnormal condition. The feet or like supporting portions 33 of the motor 26 have vertically sliding support on slotted portions 34 of the base 25. Referring 85 to Figure 5, the underside of the base is formed with a groove 35 therein extending longitudinally below each slot 34. Disposed in said slot and groove is a threaded bushing comprising a head 36 engaging in the groove and a reduced shank 37 portion 37 engaging in the slot. A cap screw 38 extends through the foot 33 of the motor base and screws into the bore of the bushing 36-37.

The shank portion 37 of the bushing is slightly longer than the depth of the slot 34 so that when the cap screw 38 is drawn up tight the outer end of said shank portion engages the underside of the foot 33 and prevents the motor from being rigidly clamped to the mounting base 25. The slight play thus maintained between the motor 100 and the mounting base permits the motor to slide downwardly on the slotted guides 34 so as constantly to maintain the driving belt 29 at the proper tension. If the belt should stretch or become worn the motor will still maintain a constant tension thereon by settling downwardly along its slotted guides, and when in such lowered position the torque pull on the belt is substantially ineffective for pulling the motor upwardly because of the tendency of the bushings 110 36-37 to bind in the slotted guides against any upward pull tending to twist the motor on the base plate.

The housing 27 is divided horizontally into upper and lower sections 27a and 27b respectively, which sections are provided with marginal joining flanges and secured together by bolts 41. Attaching lugs or flanges 42 and 43 project from the rear side of each housing section and are suitably bolted to the base plate 25, as shown 120 in Figure 3. The shaft 32 on which the large pulley wheel 31 is keyed, enters the side of the lower housing section 27b and has a worm 45 thereon intermediate spaced bearings provided for said shaft within the housing.

This worm meshes with a worm wheel 46 which is keyed to a vertical countershaft 47. The upper and lower ends of said countershaft engage respectively in bearing bushings 48 and 49 which seat in closed-end bosses 51 and 52 projecting 130 from the upper and lower housing sections. A spur pinion 53 is keyed upon this countershaft, above the worm wheel 46, and meshes with a large spur wheel 54 mounted upon the main operating axis of the device. Disposed on this axis 135 are a shaft 55 and a surrounding sleeve 56, the large spur gear 54 being keyed to the sleeve 56. Said sleeve is journaled in bushed bearing bosses or hubs 57 and 58 projecting vertically from the upper and lower housing sections. Secured by a 140 key 59 to the projecting upper end of the sleeve 56, above the upper boss 57, is the hub 61 of a driving clutch element 62, such clutch element being in the form of an annular flange projecting radially from the hub 61. Such constitutes 145 the driving element of a friction slippage clutch which is interposed in the driving train between the motor 26 and the crank arm 19 for the purpose of affording an overload relief connection so that damage to the operating parts or motor 150

cannot occur if the door should become blocked or otherwise held against its proper movement. Interposed in the line of operating parts between this friction slippage clutch and the crank 5 arm 19 is an element 63 which I have termed an actuator or rotary actuating device. This rotary actuator is secured in definitely fixed or timed relation to the cams which control the movement of the motor reversing switch, where- 10 by the actuator operates said cams in the proper timed relation.

As above remarked, the friction slippage clutch is interposed in the driving train between the electric motor and the actuator 63. Beyond this 15 actuator, or between the same and the crank arm 19 in the train of parts, is the manually actuated releasing means which permits independent movement of the crank arm 19 when it is desired to operate the door manually, as I shall presently describe. Within the broad purview of the invention the slippage clutch may be interposed at any desired point in the dividing train between the motor and the actuator 63, but in the preferred construction shown the bottom surface 63' 20 of the actuator constitutes one of the friction driven surfaces adapted to engage with the driving element 62 to be driven thereby. A cooperating lower plate 64 has its upper surface 64' engaging the lower side of the driving plate 62. The 25 two plates 63 and 64 are drawn together to effect the desired frictional contact with the driving plate 62 through the instrumentality of adjusting screws 65, Figure 7. The peripheries of the two driven plates 63 and 64 extend beyond the periphery of the driving plate 62, and the screws 65 pass down through holes in the extending portion of the upper plate and thread into bosses 66 (Figure 4) formed on the extending portion of the lower plate. By adjusting these screws any desired tension can be given the slippage clutch. 30 As shown in Figure 4, a lug 68 extends upwardly from the lower plate 64 and engages in a peripheral notch 69 in the upper plate 63 for compelling concurrent driven rotation of the two plates.

Both of these plates have bearing mounting on the upper and lower extending ends of the hub 61, the upper plate 63 having a hub portion 71 extending up above the hub 61 and formed with an inwardly extending flange or head 72. The central shaft 55 has a square or polygonal head 73 on its upper end which fits into a correspondingly shaped socket in the head portion 72. The lower end of this shaft is connected with the cams which control the motor reversing switch, and hence it 55 will be seen that the rotary actuator 63 is maintained in definitely timed relation to these cams.

The manually actuated disconnecting means, which is adapted to free the door for manual operation, may likewise be interposed at any suitable point in a line of operating connections between the actuator 63 and the crank arm 19, but in the preferred construction this manual disconnecting means is carried by the actuator 63 and is adapted to engage the hub portion of the crank arm directly. Such disconnecting means comprises two spring pressed plungers 75, 75', which are slidably mounted in arcuate bosses 76, 76' projecting upwardly from the actuator plate 63, as best shown in Figure 7. The operating 60 crank 19 has a hub portion comprising a depending annular flange 77 which is rotatably mounted over the annular flange or hub 71 of the actuator plate 63. A retaining disk 78 is seated in a circular depression in the top of the crank hub, bearing 79 against the shoulder formed at the bottom of

this depression, and being secured by screws 81 threading into the flange or head portion 72 of the actuator plate 63.

Thus the crank arm is held upon the upper end of the actuator element 63 but can be rotated relatively thereto. Normally, such rotation is prevented by the two plungers 75, 75' being projected upwardly into sockets 83, 83' formed at opposite points in the hub of the crank arm. Said plungers have reduced shank portions passing loosely through holes in the bottom clutch plate 64 and having their lower ends riveted or otherwise rigidly secured in the plate portion 84 of an annularly grooved shifting collar 85. Compression springs 86 are confined on the reduced shank portions of the plungers between the plate 64 and the head portions of said plungers, these springs normally tending to project the plungers upwardly into their respective sockets 83, 83'. The grooved shifting collar 85 is slidably mounted on the boss 57 and cooperating with this collar is a tripping yoke 88 which embraces the collar and has inwardly extending pins 89 engaging in the grooved portion thereof. A bifurcated inner end of the yoke embraces the boss 51 and is pivotally supported on lugs 91 projecting upwardly from the housing section 27a. A chain 92 extends down from the other end of said yoke and has connection with a pull ring 93, or any other suitable actuating connection whereby the yoke may be pulled downwardly for withdrawing the plunger pins 75, 75' from the sockets 83, 83' when it is desired to operate the door manually.

The plunger 75 and its socket 83 are at a different radius from the axial center of the assembly 110 than are the plunger 75' and its socket 83', so that in reestablishing the operative connection between the motor driven parts and the crank arm 19 the crank arm can only be locked to the actuator 63 in one position, which places it in 115 definitely timed relation to the cams which control the motor reversing switch.

Referring now to said cams, it will be seen from Figure 6 that the shaft 55 projects beyond the lower end of the sleeve 56 and has secured 120 thereto by a set screw 94 the hub portion 95 of an upper cam 96. The upper face of this cam may be slightly counterbored for receiving the lower end of the journal boss 58. A lower cam 97 is non-rotatably mounted on the hub portion 125 95 of the upper cam 96, being adjustably secured to said hub portion by a set screw 98. By releasing the two set screws 94 and 98 the two cams 96 and 97 can be angularly adjusted relatively to the shaft 55 and to each other.

As best shown in Figure 8, these two cams impart lateral swinging movement to a switch actuating yoke 99 having an opening 101 which embraces the journal boss 58. The pivot end of said yoke comprises an apertured portion 102 which is 130 swiveled upon the bearing boss 52, being held against displacement therefrom by a suitable nut or other retaining member 103 engaging with the end of the boss.

The opposite, swinging end of said yoke carries a projecting pin 104 which serves to throw the movable switch element or elements, as I shall presently describe. As clearly shown in Figures 8 and 9, the upper cam 96 is of smaller size than the lower cam 97, the point or rise of 140 said upper cam not extending beyond the circular peripheral edge of the lower cam 97. Projecting down from one side of the yoke 99 is a lug 105, which extends into the radius of action of the upper cam 96. This lug is of comparatively short 145 150

length so that it does not extend down into the path of movement of the lower cam 97. Extending down from the opposite side of the yoke 99 is another lug 106 which projects into the path of movement of the large cam 97. Because the point of the upper or small cam does not extend beyond the circular periphery of the large cam it cannot engage and actuate this second lug 106. In the operation of these cams, when the door reaches an almost closed position the upper, small cam 96 engages its cooperating lug 105 and swings the yoke 99 in one direction for actuating the motor reversing switch. Conversely, when the door is swung in the other direction and reaches an almost open position the lower large cam 97 engages its cooperating lug 106 and swings the yoke 99 in the opposite direction for throwing the reversing switch to its opposite position. The coasting of the electric motor insures completed movement of the door to either of its extreme positions after the switch has been thrown. The swinging end of the yoke 99 may be supported for its sidewise movement in a bracket strap 107 secured to the underside of the gear housing and forming a guide surface for the yoke.

The switch parts are enclosed within a housing 108 formed at one side or end of the lower gear housing portion 27b. Projecting downwardly through an opening in this switch housing 108 (Figure 10) is a switch operating arm or lever 109 having an inverted V-shaped opening 111 therein. The pin 104 projecting from the yoke 99 operates in this opening 111 in throwing the arm 109. As illustrated by the full and dotted line positions in Figure 10, when the pin 104 swings in either direction it carries the arm 109 with it up to the point at which the switch is thrown, and thereupon the arm can stop while the pin continues its movement in that same direction. This is provided for by the sloping ends of the V-shaped opening 111, which allows the pin 104 to pass out of the opening 111 and continue in its movement past the adjacent side wing of the switch operating lever. When the pin 104 starts back in its reverse movement it moves into the opening 111 and engages the low arm or wing of the lever, thereby carrying the lever with it until the switch has been thrown to its opposite position, whereupon the pin 104 can continue its movement out of the opening 111 and beyond the opposite side arm or wing in the same manner as described of the preceding direction of movement. By this arrangement, the pin 104 can be given excess movement in order to insure complete actuation of the switch, and still avoid the possibility of said excess movement damaging the switch.

The lever 109, in addition to actuating the motor reversing switch previously mentioned, also actuates a circuit disconnecting switch which is connected in circuit with the manually operated switch which is actuated to effect each opening and closing movement of the door. I have not deemed it necessary to illustrate the specific circuit connections because typical circuits for effecting this operation are well known, my prior Patent No. 1,594,514 illustrating an arrangement of two prior three-point switches, one manually operated and the other automatically operated, which may be employed in conjunction with a reversing switch, for effecting the desired operation of the motor in either direction with an automatic stopping of the motor at the end of each movement of the door. This or other like circuits may be employed.

In installations employing alternating current motors I have found that it is necessary or desirable to provide means for safeguarding against an abnormal condition which may possibly arise if—just at the instant that the automatically operated reversing and disconnect switches are thrown when the door is nearing one position—the manually operated switch should be actuated for causing movement of the door in the opposite direction. Such reversed actuation of the manually operated switch at this instant may result in the alternating current motor continuing to operate in the same direction after the limit of movement of the door has been reached, with the result that the continued rotation of the motor may possibly result in injury to the doors or frame construction.

To prevent this, I have provided a novel arrangement of stops which stall or retard the alternating current motor in the event of said abnormal operation of the manually actuated switch, and give one repulsion field an opportunity to die down, thus preventing the induction action of the motor from keeping the armature rotating. Referring to Figure 7, it will be seen that there are two of these stop lugs or shoulders 115 and 116 projecting from the periphery of the bottom clutch plate 64, whereby these lugs or shoulders revolve with the crank arm 19 when said crank arm is coupled to the motor drive 105 through the manually releasable plunger pins 75, 75'. These shoulders are so disposed angularly relatively to the clutch plate 64 and crank arm 19 that when the door has been moved to the closed position, illustrated in full lines in Figure 2, any tendency of the motor to keep on revolving through an appreciable interval will bring the stop shoulder 115 up against the adjacent edge 115' of the flange 42 which secures the gear housing to the base plate. Conversely, when the door has been swung to its fully open position, substantially as illustrated in dotted lines in Figure 2, any tendency of the motor to keep on revolving through an appreciable interval will bring the other stop shoulder 116 up against the other edge 116' of the mounting flange 42. Thus, if a either limit of movement of the door the motor should tend to keep on revolving in the same direction, one or the other of these stop shoulders interrupt further movement of the crank arm 19 and clutch plate 64 with the result that the motor will be stalled and one repulsion field thereof given an opportunity to die down so that the motor will stop and reverse.

In said positive stopping of the crank arm 19 and clutch plate 64 the slippage clutch 62, 64 will yield and prevent shock being transmitted to the parts. Obviously any other stationary stop projection may be arranged in lieu of the flange 42.

In order to accommodate different degrees of door-opening movement and different locations of the pivot bracket 22, the pivot 20 connecting the crank arm 19 with the link 21 is made adjustable to increase or decrease the effective length of the crank arm. As shown in Figure 11, this pivot 20 is in the form of a stud which screws into any one of a plurality of threaded holes 121 tapped at different points along the outer end of the crank arm 19. Intersecting each of these threaded holes 121 is a tapped hole 122 for receiving a set screw 123 by which the pivot stud 20 is locked in its selected hole. The end of the link 21 has any suitable sleeve mounting

on the pivot stud 20 for rotative movement thereon.

Current is supplied to the motor through conductors within a flexible conduit 125 (Figure 1) 5 extending from a stationary conduit box 126 to the switch housing 108. A second flexible conduit 127 encloses conductors leading from the switch housing 108 to the motor 26. The manually actuated switch by which each movement 10 of the door is started is indicated at 128, such switch being located at any convenient point of operation.

From the preceding description, it will be evident that for opening the door the switch 128 is 15 actuated whereupon the door swings to its open position and near the completion of such movement automatically throws the switch arm 109 to disconnect the motor and reverse its windings. Thereupon, to close the door the switch 128 is 20 again actuated, which closes the circuit for the motor, causing it to operate in the reverse direction and swing the door to closed position, at the completion of which movement the switch arm 109 is again thrown to its opposite position for disconnecting the motor and reversing its windings. 25 The throw of the switch arm 109 occurs just prior to the completion of the door closing movement so that the coast of the motor carries the door up against the frame stops. The overload relief 30 connections afforded through the slippage clutch 62-64 and through the belt drive 29 absorb any remaining momentum of the motor when the door is positively stopped. The throwing of the switch mechanism can be made to occur at any 35 given point in the movement of the door by appropriately adjusting one or both cams 96, 97.

If the normal movement of the door should be 40 blocked or resisted the overload relief clutch 62-64 will yield and prevent injury to the mechanism.

The belt drive 29 will also assist in this regard. As previously pointed out, however, such slippage 45 of the clutch or of the belt drive will not disturb the normal timed relation of the cams 96, 97 to the position of the door, these cams remaining positively connected to the rotary actuating element 63. Moreover, after the functioning of the slippage clutch it is not necessary to manually 50 reset any part of the mechanism in order that the movement of the door may be continued. By adjusting the screws 65, the relief clutch may be made to yield at any predetermined overload torque.

For manually operating the door independently 55 of the energization of the electric motor, it is only necessary to pull the tripping chain 92, which withdraws the plungers 75, 75' from the sockets 83, 83' and frees the crank arm 19 from the actuating element 63. After the completion of such 60 manual movement, the crank arm 19 can only be restored to operative connection with the actuating element 63 in one angular position, because of the different spacing of the sockets 83, 83', which insures that the crank arm will be restored 65 to proper timed relation to the cams 96, 97.

As previously described, if because of improper 70 actuation of the manually operated switch 128 the motor should tend to continue to revolve in the same direction at the completion of one door movement one or the other of the stops 115, 116 will positively interrupt further movement of the crank arm in the direction and stall or retard the motor for discontinuing its continued rotation in that direction.

75 It will be noted that such functioning of the

stops 115, 116 does not disturb the timed relation of the cams 96, 97.

When the door is in closed position it is effectively locked against unauthorized opening from the outside. The manually operated releasing means is only operable from the inside. Also, as shown in Figure 1, the crank arm 19 and link 21 are at this time in approximately dead center relation so that pressure exerted against the outer side of the door does not operate with sufficient mechanical advantage to cause slippage of the friction clutch 62-64.

While the particular construction which I have shown and described constitutes what I regard to be the preferred embodiment of my invention, nevertheless it will be understood that such is merely exemplary and that numerous modifications and rearrangements of parts may be made without departing from the essence of the invention.

I claim:

1. The combination with a closure member and a fixed support relatively to which said closure member has movement, of mechanism for operating said closure member and adapted to be mounted thereon, said mechanism comprising a crank arm arranged to have operative connection with said fixed support, an electric motor mounted for vertical movement relative to said mechanism, and driving means connecting said electric motor with said crank arm including a flexible overload slippage connection, said motor being movable vertically to automatically maintain said flexible connection under normal driving tension.

2. The combination with a closure member and a fixed support relatively to which said closure member has movement, of mechanism for operating said closure member and adapted to be mounted thereon, said mechanism comprising a crank arm arranged to have operative connection with said fixed support, an electric motor, driving means connecting said electric motor with said crank arm, and manually operable releasing means for disconnecting the closure member from said electric motor, said releasing means comprising parts disposed at different radii from the axial center of said releasing means and only reconnectable when said closure member is in predetermined timed relation to said operating mechanism.

3. The combination with a closure member and a fixed support relatively to which said closure member has movement, of mechanism for operating said closure member and adapted to be mounted thereon, said mechanism comprising a crank arm arranged to have link connection with said fixed support, an actuating element for swinging said crank arm, an electric motor for driving said actuating element, and readily operable manual releasing mechanism between said crank arm and said actuating element and comprising means disposed at different radii from the axial center of said releasing means for compelling the reconnection of said actuating element and crank arm only in predetermined angular relation.

4. The combination with a door and a door-way, of mechanism for operating said door and adapted to be mounted thereon, said mechanism comprising a crank arm arranged to have link connection with said door-way, an electric motor, driving means connecting said electric motor with said crank arm including overload relief means, said latter means comprising an annular driving member and an annular driven member effective

to transmit operating torque to said crank arm with said members in any relative angular position, and manually operable means carried by one of said annular members and comprising a plurality of plungers for releasably engaging within sockets formed in said crank arm for normally operating said door.

5. The combination with a door and a door-way, of mechanism for operating said door, and adapted to be mounted thereon, said mechanism comprising a reversely swinging crank arm adapted to have operative connection with said door-way, a reversible electric motor, driving means for connecting said electric motor with said crank arm comprising an actuating element, an overload relief slippage clutch capable of yielding in either direction of rotation interposed in said driving means between said electric motor and said actuating element, and manually operable releasing means interposed in said driving means between said actuating element and said crank arm and comprising a shiftable collar and means carried by said collar for directly engaging said crank arm.

25 6. The combination with a door and a door-way, of mechanism for operating said door, and adapted to be mounted thereon, said mechanism comprising a reversely swinging crank arm adapted to have operative connection with said door-way, a reversible electric motor, driving means for connecting said electric motor with said crank arm comprising an actuating element, an overload relief slippage clutch capable of yielding in either direction of rotation interposed in said driving means between said electric motor and said actuating element, manually operable releasing means interposed in said driving means between said actuating element and said crank arm comprising a shiftable collar and a plurality of 40 plungers carried by said collar for directly engaging said crank arm, cam means responsive to said actuating element, and reversing switch means responsive to said cam means for controlling said electric motor.

45 7. The combination with a door and a door-way, of a door-operating unit mounted on said door and comprising a reversely swinging crank arm, a link pivotally connected between said crank arm and the door-way, a reversible electric motor mounted on the door, mechanism connecting said electric motor with said crank arm comprising a shaft, an actuating element secured to said shaft and oscillating the latter, a friction slippage clutch capable of yielding in either direction of rotation mounted concentrically of said shaft and operatively connected between said electric motor and said actuating element, manually released clutching means including a shiftable collar separate from said slippage clutch and mounted concentrically of said shaft and normally establishing a positive driving relation between said actuating element and said crank arm, cam means responsive to said shaft and motor reversing switch means responsive to said cam means.

35 8. A door operator of the class described for mounting on the door, comprising a crank arm adapted to have link connection with a stationary support, an electric motor, a concentric shaft and sleeve, capable of relative rotation reduction gearing operatively connected to drive said sleeve from said motor, a friction slippage driving clutch element secured to said sleeve, a cooperating friction slippage driven clutch element connected with said crank arm, said crank arm seating directly upon said driven clutch element and said

driven clutch element and said shaft moving together, and motor reversing switch means responsive to the movement of said shaft, to control said door.

9. A door operator of the class described for mounting on the door, comprising a crank arm member adapted to have link connection with a stationary support, an electric motor, a concentric shaft and sleeve, capable of relative rotation reduction gearing operatively connected to drive said sleeve from said motor, a friction slippage driving clutch element secured to said sleeve, a cooperating friction slippage driven clutch element connected with said crank arm, said crank arm seating directly upon said driven clutch element and said driven clutch element and said shaft moving together, motor reversing switch means responsive to the movement of said shaft, and manually operable means for interrupting the transmission of motion from said driven clutch element to said crank arm.

10. A door operator of the class described adapted for mounting on the door, comprising a crank member adapted to have pivoted link connection with a stationary support, an electric motor, a rotating member driven by said electric motor and mounted concentrically of said crank member, and manually actuated releasing means for operatively connecting said crank member with said rotary member and comprising 100 pin means carried by said rotary member adapted to engage in socket means formed in said crank member, said pin and socket means being arranged whereby the driving relation between said rotating member and said crank member can only be reestablished with said members in predetermined angular relation to each other.

11. A door operator of the class described adapted for mounting on the door, comprising a substantially vertical rotatable member, an electric motor, a worm driven by said electric motor, a worm wheel driven by said worm, a countershaft on which said worm wheel is mounted, spur gears mounted on said rotatable member and on said countershaft for transmitting rotation from said worm wheel to said rotatable member, a crank arm mounted at the upper end of said rotatable member and adapted to have pivotal link connection with a stationary support for operating the door, and reversing switch means responsive to the movement of said crank arm for controlling said electric motor comprising a yoke encircling said countershaft and loosely embracing said vertical rotatable member for lateral swinging movement.

12. In a door operator adapted for mounting on the door, the combination of a crank arm adapted to have pivotal link connection with a stationary support, an electric motor, driving means operatively connecting said electric motor with said crank arm, cam means arranged to be moved by said crank arm, automatic switch means controlling said electric motor, and a pivotally swinging yoke member embracing said cam means and positively oscillated in opposite directions by said cam means for effecting movement of said switch means.

13. A door operator of the class described adapted for mounting on the door, comprising a crank arm adapted to have pivoted link connection with a fixed support, a rotatable member on which said crank arm is mounted, an electric motor, a shaft above said motor, operating connections between said shaft and said rotatable member, a belt drive between said electric motor and

said shaft, and mounting means for said motor on which said motor can move downwardly whereby the weight of the motor is effective to hold said belt at the proper driving tension.

5 14. A door operator of the class described adapted for mounting on the door, comprising a crank arm adapted to have pivotal link connection with a fixed support, an electric motor, driving means operatively connecting said electric motor with said crank arm, a rotatable member moving with said crank arm, a pair of cams on said rotatable member, a pivotally swinging yoke cooperating with said cams, one of said cams having a cam rise of comparatively small radius, 10 a shoulder on said yoke adapted to be engaged by said cam rise, the other of said cams having a cam rise of relatively large radius, a second shoulder on said yoke clearing said first cam and extending into the path of the cam rise of said latter cam, and switch means responsive to the movement of said yoke for controlling said electric motor.

15 15. A door operator adapted for mounting on the door, comprising a crank arm adapted to have pivoted link connection with the door-way, 25 an electric motor, driving means operatively connecting said motor with said crank arm, cam means moved by said crank arm, a pivotally swinging member actuated by said cam means, switch means for controlling said motor comprising a switch actuating arm pivoted for swinging movement in a plane substantially at right angles to the movement of said pivotally swinging member, said switch actuating arm having a V-shaped opening therein, and a pin on said pivotally swinging member adapted to engage in said opening for imparting movement to said switch actuating arm, said pin being capable of continued movement out of said opening and beyond said arm after the switch has been thrown.

40 16. The combination with a swinging door and a door-way, of a door operating unit mounted on said door, and comprising a housing, a vertically extending sleeve journaled in said housing and having its upper end projecting therefrom, a shaft extending through said sleeve with the opposite ends extending therefrom and its lower end projecting below said housing, a countershaft journaled in said housing, a worm wheel mounted on said countershaft, a worm meshing therewith, an electric motor connected to drive said worm, a spur gear mounted on said countershaft, a spur gear keyed to said sleeve and meshing with said latter spur gear, both of said spur gears being enclosed within said housing, a driving friction clutch disk secured to the projecting upper end of said sleeve above said housing, upper and lower driven friction clutch disk engaging with the upper and lower sides of said driving disk, adjustable means for establishing frictional pressure between said disks, said upper frictional disk being secured to the projecting upper end of said shaft, a crank arm having its hub rotatably mounted above said upper friction disk, a pair of spring pressed plungers carried by said two driven disks and normally urged upwardly into sockets in said crank arm, a shifting collar to which said plungers are connected, a tripping member connected with said collar and adapted to be manually actuated for withdrawing said plungers from said sockets, a pair of cams secured to the projecting lower end of said shaft, a pivotally swinging yoke comprising portions engaged by said cams for oscillating said yoke in opposite directions, switch means responsive to

the movement of said yoke for controlling said electric motor, and a link pivotally connected between the swinging end of said crank arm and a fixed point of pivotal attachment on said door-way.

80 17. In a door operator of the class described adapted for mounting on the door, the combination of an electric motor, a driving frictional clutch element, means for transmitting power from said motor to said clutch element for rotating the latter, a driven frictional clutch element, a crank arm seated upon and swung by said driven clutch element and adapted to be connected for moving the door, reversing switch means responsive to the movement of the door for controlling said motor, and stop means moving with said driven clutch element for preventing said motor from accidentally continuing rotation in one direction after said door has reached the limit of its movement in one direction and after said reversing switch means has been thrown.

85 18. The combination with a closure member and a stationary member relatively to which said closure member has movement, of mechanism for operating said closure member comprising a swinging crank having link connection to one of said members and actuated by a rotating driven disk, a rotatable shaft to which said driven disk is secured, a sleeve mounted for relative rotation 100 on said shaft, a driving clutch disk fixed on said sleeve and frictionally contacting one surface of said driven disk, a second driven clutch disk frictionally contacting another surface of said driving clutch disk, a shiftable collar mounted 105 concentrically with said friction clutch disks and adapted to move longitudinally of the axis of said shaft and sleeve, and plunger means associated with said collar and engaging socket means in said crank for normally locking said crank 110 for rotative movement with said driven clutch plates and shiftable collar.

115 19. The combination with a closure member and a stationary member relatively to which said closure member has movement, of mechanism for operating said closure member comprising a swinging crank having link connection to one of said members and actuated by a rotating disk, a rotatable shaft on which said disk is non-rotatably mounted, a sleeve mounted for relative rotation 120 on said shaft, a driving clutch disk non-rotatably mounted on said sleeve and frictionally contacting one surface of said driven disk, a second driven clutch disk frictionally contacting another surface of said driving clutch disk, a shiftable 125 collar mounted concentrically of said sleeve and adapted to move longitudinally of the axis of said shaft and sleeve, a spring pressed plunger connected to said shiftable collar and passing through said friction disks, said plunger adapted 130 to register with socket means in said crank for releasably locking the latter for concentric movement with said friction clutch plates and said shiftable collar, and manually operative means for moving said collar away from said clutch 135 plates whereby said plunger is disengaged from said crank thereby allowing independent movement of said closure member.

140 20. The combination with a closure member and a stationary member relatively to which said closure member has movement, of mechanism for operating said closure member comprising a rotating sleeve, a friction clutch disk keyed to said sleeve, a pair of driven clutch plates frictionally embracing said disk, the outer peripheries of said 145

driven clutch plates extending beyond the outer periphery of said disk, a shiftable collar mounted concentrically of said friction clutch plates, said collar adapted to move longitudinally of said sleeve, a plunger actuated by said collar, said plunger extending through the outer peripheries of said clutch plates and releasably engageable in socket means in said crank to lock the latter in operative relationship with said driven clutch plates, and a manually operative lever adapted to actuate said collar whereby said closure member may be actuated independently of said mechanism.

21. The combination with a closure member and a stationary member relatively to which said closure member has movement, of mechanism for operating said closure member comprising a swinging crank having link connection to one of said members, a vertically extending rotatable member, a driving clutch disk having a hub portion keyed to said member, driven clutch plates mounted on opposite sides of and frictionally contacting said driving disk for rotating said plates, one of said driven plates having a hub portion mounted on the hub of said driving disk, a sleeve formed on one end of said crank and rotatably mounted on the hub of said driven clutch plate for actuating said crank, a shiftable collar mounted concentrically with said plates and adapted for movement longitudinally of said vertically extending member, a plunger associated with said collar and passing through the outer peripheries of said driven clutch plates, said plunger adapted to releasably engage said crank relatively to said clutch plates, and a manually operative lever for actuating said collar to disengage said plunger from said crank whereby the sleeve of said crank will rotate relative to said driven clutch plate in actuating said closure member independently of said mechanism.

22. The combination with a closure member and a stationary member relatively to which said closure member has movement, of mechanism for operating said closure member comprising a swinging crank having link connection to one of said members, a vertically extending rotatable member, a driving clutch disk having a hub portion keyed to said member, driven clutch plates

mounted on opposite sides of and frictionally contacting with said driving disk for rotating said plates, the outer peripheries of said plates extending beyond the outer margin of said driving clutch disk, one of said driven plates having a hub portion mounted on the hub of said driving disk, a sleeve formed on one end of said crank and rotatably mounted on the hub of said driven clutch plate for actuating said crank, a shiftable collar mounted concentrically with said plates and adapted for movement longitudinally of said vertically extending member, a plunger associated with said collar and passing through the outer peripheries of said driven clutch plates, said plunger adapted to releasably engage said crank relatively to said clutch plates, and a manually operative lever for actuating said collar to disengage said plunger from said crank whereby the sleeve of said crank will rotate relative to said driven clutch plate in actuating said closure member independently of said mechanism.

23. The combination with a closure member and a stationary member relatively to which said closure member has movement, of mechanism for operating said closure member comprising a reversible electric motor, a crank having link connection to one of said first named members, a vertically extending shaft on which said crank is mounted, a vertically extending countershaft spaced laterally from said other shaft, a housing in which said shafts are journaled, a train of gears for driving said shaft and countershaft, one of said gears being a worm gear, a horizontal shaft driven by said electric motor, a worm on said latter shaft meshing with said worm gear, a slip clutch disposed between said electric motor and said crank for disengaging said motor, an actuating switch for producing reverse rotation of said motor to alternatively open and close said closure member, and means including a laterally swinging yoke member pivoted to the journal of said countershaft, and loosely embracing said vertically extending shaft for actuating said switch.
